UNITED STATES PATENT OFFICE.

JACKSON T. HALE, OF FULTON COUNTY, GEORGIA, ASSIGNOR OF ONE-THIRD TO
CHRISTOPHER LA FAYETTE HARTWICK, OF CLEVELAND, TENNESSEE.

INTERNAL-COMBUSTION ENGINE.

Application filed March 27, 1924. Serial No. 702,404.

To all whom it may concern:

Be it known that I, JACKSON T. HALE, a citizen of the United States, residing in the county of Fulton and State of Georgia, have 5 invented a certain new and useful Improvement in Internal-Combustion Engines, of which the following is a full, clear, and exact description.

This invention relates to internal combustion engines, and particularly to such engines wherein provision is made for firing of the combustible charge when the crank of the crank shaft to which the piston of the firing cylinder is connected is past dead center, whereby maximum power effect of the combustible charge is obtained and back kick prevented.

The main object of my invention is the provision in such an engine of means whereby the combustible charge, although fired or ignited at a time when the crank is past dead center may be maintained at maximum compression until it is fired.

The invention consists in an internal combustion engine of the type mentioned, wherein in the top of the combustion chamber is in the form of a follower or compression piston, and in particular means for actuating said piston, whereby, upon the firing or 30 power stroke of the power piston of the engine, said compression piston will descend in unison with the descent of the power piston, to a predetermined extent, for the purpose of maintaining the combustible charge at maximum compression until ignition of said charge takes place.

In the accompanying drawings illustrating the invention, in the several figures of which like parts are similarly designated. Figure 40 1 is a vertical transverse section of an engine embodying my invention, taken in the plane of line 1—1, Fig. 3. Fig. 2 is an end view of the engine with parts broken away on line 2—2, Fig. 3, to show the means for actuating the compression pistons. Fig. 3 is a longitudinal vertical section through two adjacent cylinders of a multiple cylinder engine constructed in accordance with my invention.

50 The cylinder casting 1 is suitably mounted upon the usual base 2 provided with a crank case 2'. The cylinder 1 has a separable head 3 provided with the usual valve chamber 4. Working in the cylinder 1 is 55 the power piston 5 connected by a connect-

ing rod 6 with the crank shaft 7 which is mounted in the usual bearings in the base 2.

The cylinder head 3 is elongated to accommodate a follower or compression piston 8 connected by a connecting rod 9 with a 60 rock shaft 10 mounted in suitable bearings 11 on the top of the cylinder head.

This connecting rod 9 extends through a slot 12 in the top of the cylinder head, and any suitable means such as the slides 13 and 65 swivelling bushings 14 may be provided for closing the opening formed in the top of the cylinder head by this slot.

On the outer end of the rock shaft 10 is mounted a crank arm 15 connected through 70 a stud 16 with a link 17, which link is slotted at its lower end as at 18 to ride upon and be guided by the end of the crank shaft 7. Adjacent to the crank shaft embracing end of the link 17 is a cam 19 arranged for constant operative engagement with rollers 20 and 21 carried by the end of the link 17 75 above and below the cam respectively. These rollers are mounted upon studs 22 and may, if desired, be provided with ball or 80 other anti-friction bearings 23.

By this arrangement it will be seen that upon rotation of the crank shaft 7 and consequent rotation therewith of the cam 19, the link 17 by means of the cooperation of 85 its rollers 20 and 21 with the cam 19 will be vertically reciprocated and will, in such reciprocation, impart an oscillatory movement to the rock shaft 10, which in turn, through its connection 9 with the piston 8, will reciprocate this piston in a manner to be hereinafter described.

As will be seen, particularly by reference to Fig. 3, all of the mechanism for actuating the link 17 is enclosed within the crank 95 case compartment, and is therein provided with constant and efficient lubrication.

I have hereinabove described the mechanism of only one cylinder, but it will be apparent that all of the parts are the same 100 for each cylinder of a multi-cylinder engine; except that one rock shaft 10 and its operating mechanism alone is required for any desired number of cylinders, the setting of the cranks on such shaft being determined by the order of firing of the several cylinders.

The operation of the device is as follows:—Taking the parts of the mechanism in the positions in which they are shown in 110

Fig. 1, and assuming that the crank shaft 7 is turning in the direction of the arrow, the parts are in the positions they will assume at the limit of the compression stroke of the engine, and, the engine as designed being of the four-stroke cycle type, I will trace the operation of the various parts throughout the firing, exhausting and intake strokes. We will assume that a charge has been compressed and that the piston 5 is about to descend upon the firing stroke. As hereinbefore pointed out, my engine is designed to fire when the crank of the firing cylinder is well past dead center or, for example, when in the position indicated by the dotted lines marked *a* in Fig. 1. Now as the crank 7, which has, we will say, acquired momentum from the explosion of previous charges, rotates, the piston 5 will be lowered in the cylinder, and at the same time the cam 19 will rotate and its portion *x* will, through co-operation with the roller 20, depress the link 17, and, through this link and its connection with the rock shaft 10, will lower the follower or compression piston 8 in the cylinder head. The cam 19 is so designed that this movement of piston 8 will continue until the power piston 5 has descended to the dotted line position *a* above mentioned, at which time the portion *y* of cam 19 will be operating upon the roller 20. This portion *y* of the cam being concentric with the crank shaft, the piston 8 will be held in this lowered position while the charge is fired, and will rise again during the exhaust stroke of the piston 5. The contour of the cam is such that the compression piston is moved slowly during the first part of its downward stroke and this motion is gradually accelerated until the limit of movement is reached, thus simulating the movement of the power piston and maintaining the space between the two substantially constant. It will, moreover, be noted that the cam 19 is so shaped that while the roller 21 is being operated upon to depress the link 17, the roller 20 is following the cam on a point diametrically opposite to the point of contact of the roller 21, and when the cam is operating upon the roller 20 to impart an upward movement to the link 17, the roller 21 will similarly follow the diametrically opposite point of the cam from the roller 20. It will thus be seen that, both rollers being at all times in operative contact with the cam 19, a positive reciprocation in both directions is imparted to the link 17, and this positive movement is transmitted through the arm 15 to the rock shaft 10.

When the piston 8 is at the limit of its downward movement, its connecting rod 9 and the crank of the rock shaft 10 to which it is connected are in direct vertical alignment with the center of the rock shaft, and

as it is at the time when these parts are so positioned that the ignition of the charge takes place, the force of the explosion will be borne directly by the rock shaft, which is of such rugged construction as to well 70 withstand the shock, and very little if any of this shock will be imparted through the rock shaft and its connections to the link 17 and cam and rollers 19, 20 and 21 respectively, thus saving wear upon the various 75 bearings interposed in the connections of these parts and providing for the reception of the shock of the explosion upon a part designed to withstand it.

When the exhaust stroke has been completed, as hereinbefore indicated, the cam 19 will have turned through 360° and will have returned to the position shown in Fig. 1, thus also returning the piston 8 to the position shown. Obviously, during the intake and compression strokes, the motions imparted to the piston 8 through the cam and other connections will be the same as those imparted during the firing and exhaust strokes.

Although ignition is so timed as to occur when the crank is past dead center, no compression is lost owing to the fact that the size of the combustion chamber is maintained constant from the time that the power piston 5 reaches the top of its compression stroke to the time of ignition of the charge. Not only does this ignition timing tend to increased efficiency of the engine and consequent economy in fuel consumption, but it prevents back kick due to preignition.

Although I have herein shown and described my invention as applied to a multi-cylinder engine of the vertical type, it is obvious that it is also applicable to horizontal, 105 V, and other types of engines.

Various changes in construction and arrangement of parts are contemplated as within the spirit of the invention and the 110 scope of the following claims.

What I claim is:

1. In an internal combustion engine, a power cylinder, a power piston working therein, a crank shaft and a connection between said piston and crank shaft, a compression piston arranged in said cylinder above said power piston and adapted to move in unison therewith throughout a portion of the power stroke, and to remain stationary during the remainder of said stroke, and means for imparting such movement to said compression piston including a cam carried by and revoluble with said crank shaft and a link provided with rollers contacting with said cam at diametrically opposite points on the periphery thereof, said link being suitably connected with said compression piston to impart movement thereto in response to the movement imparted to said link by said cam.

2. In an internal combustion engine, a power cylinder, a power piston working therein, a crank shaft and a connection between said piston and crank shaft, a compression piston arranged in said cylinder above said power piston and adapted to move in unison therewith throughout a portion of the power stroke, and to remain stationary during the remainder of said stroke, 5 and means for imparting such movement to said compression piston including a cam carried by and revoluble with said crank shaft, a rock shaft mounted in bearings 10 above the cylinder head, a connection between said rock shaft and compression piston, and a link connected to said rock shaft and provided with rollers engaging said cam at diametrically opposite points of its periphery, whereby a reciprocatory motion is imparted to said link and an oscillatory motion imparted through said link to said rock shaft. 15
- In testimony whereof I have hereunto set my hand this 26th day of March A. D. 1924. 20

JACKSON T. HALE.
